UNITED STATES PATENT OFFICE

139,476

DESIGN FOR A RADIAL ARM SAW

Burke Miller, Kansas City, Mo.

Application August 5, 1944, Serial No. 114,746

Term of patent 14 years

(Cl. D93—3)

To all whom it may concern:

Be it known that I, Burke Miller, a citizen of the United States, residing at Kansas City, in the county of Jackson and State of Missouri, have invented a new, original, and ornamental Design for a Radial Arm Saw, of which the following is a specification, reference being had to the accompanying drawings, forming a part thereof.

Fig. 1 is a perspective view of a radial arm saw, showing my new design; and

Fig. 2 is a side elevational view thereof.

I claim:

The ornamental design for a radial arm saw, as shown.

BURKE MILLER.
